H. DAVIES

ELECTRICAL FUSE

Filed Jan. 26, 1920

FIG. I

FIG. II

FIG. III

FIG. IV

UNITED STATES PATENT OFFICE.

HOWARD DAVIES, OF PHILADELPHIA, PENNSYLVANIA.

ELECTRICAL FUSE.

Application filed January 26, 1920. Serial No. 354,175.

To all whom it may concern:

Be it known that I, HOWARD DAVIES, a citizen of the United States, residing at Philadelphia, in the county of Philadelphia 5 and State of Pennsylvania, have invented a certain new and useful Improvement in Electrical Fuses, whereof the following is a specification, reference being had to the accompanying drawing.

10 My invention relates to fuses of the general class including a tubular casing of insulating material having metallic terminals at its opposite ends adapted to detachably secure a strip of fusible metal, and 15 having means to electrically connect such fuse strip with conductors leading to and from said casing; and relates to the specific class of such fuses contemplated in my pending application Serial No. 332,213 for 20 Letters Patent of the United States, in that the terminals comprise wedge abutments which are respectively fixed in the fuse casing at opposite ends thereof and adapted to co-operate with wedges which are movable in 25 said casing in opposition to the respective abutments, to detachably secure the opposite ends of a fuse strip between them. However, in the structures described in that 30 application, the movable wedges are independent of the fuse casings and provided with circumferential grooves, which the operator may engage with a screw driver or similar implement adapted to be used as a lever to pry the wedges out of said casings 35 when it is desired to renew the fuse, whereas, in accordance with my present improvement, the movable wedges may be so connected with the terminal screw caps which are parts of the terminal fuse casings that 40 the operator may remove them with said caps by simply unscrewing the latter, and without the employment of any other implement.

Moreover, my invention includes various 45 novel features of construction and arrangement hereinafter more definitely specified, particularly with reference to the construction and arrangement of the means for holding said screw caps in normal position.

50 In the drawing; Fig. I is a side elevation of a fuse embodying my invention.

Fig. II is a longitudinal sectional view 55 of said fuse taken on line II, II in Fig. I.

Fig. III is an end view of said fuse as shown in Fig. I.

Fig. IV is a side elevation of a fuse embodying a modified form of my invention.

Fig. V is a longitudinal sectional view 60 of said fuse, taken on the line V, V in Fig. IV.

Fig. VI is a transverse sectional view taken on the line VI, VI in Fig. II.

Fig. VII is a transverse sectional view taken on the line VII, VII in Fig. V.

Referring to the form of my invention shown in Figs. I to III inclusive; the cylindrical tubular casing 1 is composed of insulating material, conveniently vulcanized fiber, and has the metallic screw nipples 2 threaded therein at its opposite ends and 70 fastened with the respective set screws 3 which also hold the semicylindrical metallic wedge members 5 which have their inner faces 6 extending in planes which are oblique to the axis of said casing 1, so as to 75 afford respective wedge abutments, in opposition to the parallel plane inclined faces 8 of the respective complementary semicylindrical wedges 9. Said wedges 9 are movable axially in said casing 1, to clamp the 80 respective ends of the fuse strip 10 between said wedges 9 and said wedge abutments 5, but in contact with the elements 12 with which said abutments are faced, as shown in Fig. II. As indicated in dotted lines 85 in Fig. I, said fuse strip 10 is much wider at its ends, which are engaged with the wedge elements aforesaid, than at its intermediate portion; the latter being of a cross sectional area which is precisely predetermined in accordance with the rated 90 capacity of the fuse. Such capacity is manifested by marks on each strip appearing exterior to said casing as shown in Fig. III. Said wedges 9 may be pressed into 95 the position shown in Fig. II, by rotation of the terminal screw caps 11 which have internal screw threads engaging said nipples 2; the inclination of said plane faces of the wedge members aforesaid being such 100 as to afford adequate clamping action throughout the entire surfaces of said fuse strip 10 which are engaged by the respective terminals.

Said abutments 5 are provided with separable electrical conducting elements 12, also held by said set screws 3 and which serve as blades for detachable electric connection between opposite spring plates, of any suitable construction, which are indicated at 110

in Fig. II. In order to operatively connect said wedges 9 with said screw caps 11, so that the latter may be turned to move said wedges axially, without turning said wedges; 5 I find it convenient to provide each of said wedges 9 with a rivet lug 15, which extends through the two metallic washers 16 and 17, respectively inside and outside of the inwardly extending annular flange 19 of the 10 respective cap 11 at the left hand side of Fig. II, so that although said cap flange 19 may turn freely between said washers, such turning movement causes said flange to thrust upon one or the other of said washers 15 and shift said wedge 9 accordingly. In order to hold said washers in concentric relation, I find it convenient to also couple them by rivets 21. I also find it convenient to interpose a packing washer 22, of insulating material, such as asbestos composition, between said washers 16 and 17 and 20 said cap flange 19, which prevents the outlet of flame from the casing when the fuse blows. However, it is to be understood that 25 such insulating washers 22 may be omitted, without impairing the function of said washers 16 and 17. Moreover, as illustrated at the right hand side of Fig. II; all of said washers 16, 17 and 22, may be omitted; in 30 which case the wedge 9 may be operatively connected directly with the terminal cap by means of the lug 29 extending from the wedge 9 and overlapping the edge of the cap flange 19.

35 Of course, such a fuse as above described, with reference to Figs. I to III inclusive, may be made without the blade elements 12, if the fuse is to be included in a circuit by connection at each end between spring 40 plates bearing directly upon said caps 11. However, for a fuse of that latter type, I prefer to further simplify the construction, as shown in Figs. IV and V, wherein the cylindrical tubular casing 31 is composed of 45 insulating material, for instance, vulcanized fiber, and has the metallic screw nipples 32 at its opposite ends, which are not threaded therein like the nipples 2 aforesaid, but have respective annular flanges 33 and 34 50 extending over said casing 31. As best shown at the left hand side of Fig. V, the flange 33 is internally screw threaded to engage an external screw thread on the casing 31, but, as shown at the right hand side 55 of Fig. V, the flange 34 is not internally screw threaded but is smoothly cylindrical and merely fitted over the adjacent end of the casing 31. Said screw nipples 32 are fastened with respective rivets 36 which extend through the respective flanges 33 and 34 and the adjacent wall of the casing 31 and also hold the semicylindrical metallic wedge members 37 which have their inner faces 38 extending in planes which are oblique to the axis of said casing 1, so as to 60 afford respective wedge abutments, in opposition to the parallel plane inclined faces 40 of the respective complementary semicylindrical wedges 41. Said wedges 41 are movable axially in said casing 31, to clamp the 70 respective ends of the fuse strip 42 between said wedges 41 and said wedge abutments 37. Said wedges 41 may be pressed into the position shown in Fig. V, by rotation of the terminal screws caps 43 which have internal screw threads engaging said nipples 32; the inclination of said plane faces of the wedge members 37 and 41 aforesaid being such as to afford adequate clamping action 80 throughout the entire surfaces of said fuse strip 42 which are engaged by the respective terminals. I find it convenient to provide each of said wedges 41 with a screw 45 which extends axially through the adjacent cap 43 so that although said caps may 85 turn freely, with respect to said wedges, such turning movement causes said caps to thrust said wedges in or draw them out in accordance with the direction of the turning movement, thus lessening the cost of 90 construction by the omission of the washers 16, 17 and 22 and their appurtenances above described. Therefore, it appears that fuses embodying my invention may be made in at least four different ways above contemplated, to wit, first, a fuse having both ends like the left hand end of the fuse shown in Fig. II; second, a fuse having both ends like the right hand end of the fuse shown in Fig. II; third, a fuse having both ends like 100 the left hand end of the fuse shown in Fig. V and, fourth, a fuse having both ends like the right hand end of the fuse shown in Fig. V.

Therefore, I do not desire to limit myself 105 to the precise details of construction and arrangement herein set forth, as it is obvious that various modifications may be made therein without departing from the essential features of my invention as defined 110 in the appended claims.

I claim:

1. In an electrical fuse structure; the combination with a cylindrical tubular casing of insulating material, having screw threads at its opposite ends; of metallic screw nipples at said ends; means fastening said nipples, including respective elements extending radially through said casing and said nipples; substantially semicylindrical metallic terminal members held in said nipples by said fastening means and having their inner faces extending in planes which are oblique to the axis of said casing, affording respective wedge abutments; wedges respectively axially movable in said casing in opposition to said wedge abutments, having their inner faces respectively inclined parallel with the inclined faces of said abutments; whereby said wedges are adapted to 125 130

- clamp a fuse strip; said wedges having means to effect their withdrawal, including members projecting from the ends thereof; screw caps respectively fitted to the outer ends of said nipples; each having an inwardly projecting annular flange; said caps having respective openings for electrical conductors; electrical conducting elements, respectively extending from said wedge abutments, formed as plane blades which are held in alinement with each other by said abutments; and a fuse strip extending in said casing, having its opposite ends clamped by said wedge members.
2. In an electrical fuse structure; the combination with a tubular casing of insulating material, having screw threads at its opposite ends; of metallic screw nipples on said casing at its opposite ends; means fastening said nipples, including respective elements extending radially in said casing and said nipples; substantially semicylindrical metallic terminal members held in said nipples by said fastening means and having their inner faces extending in planes which are oblique to the axis of said casing, affording respective wedge abutments; wedges respectively axially movable in said casing in opposition to said wedge abutments, having their inner faces respectively inclined parallel with the inclined faces of said abutments; whereby said wedges are adapted to clamp a fuse strip; each of said wedges having means to effect its withdrawal, including a projection at the outer end thereof; screw caps respectively fitted to the outer ends of said nipples; each having an inwardly projecting annular flange engaging the adjacent wedge projection; and a fuse strip extending in said casing, having its opposite ends clamped by said wedge members.
3. In an electrical fuse structure; the combination with a tubular casing of insulating material; of metallic screw nipples on said casing at its opposite ends; means fastening said nipples, including respective elements extending radially in said casing and said nipples; substantially semicylindrical metallic terminal members held in said nipples by said fastening means and having their inner faces extending in planes which are oblique to the axis of said casing, affording respective wedge abutments; wedges respectively axially movable in said casing in opposition to said wedge abutments, having their inner faces respectively inclined parallel with the inclined faces of said abutments; whereby said wedges are adapted to clamp a fuse strip; each of said wedges having means to effect its withdrawal, including a projection from the outer end thereof; and screw caps respectively fitted to the outer ends of said nipples; each detachably engaging the adjacent wedge projection; whereby each wedge may be removed by turning its cap.
4. In an electrical fuse structure; the combination with a tubular casing of insulating material; of metallic screw nipples on said casing at its opposite ends; metallic terminal members in said nipples having their inner faces extending in planes which are oblique to the axis of said casing, affording respective wedge abutments; wedges respectively axially movable in said casing in opposition to said wedge abutments; whereby said wedges are adapted to clamp a fuse strip between them and their respective abutments; each of said wedges having means to effect its withdrawal, including a projection from the outer end thereof; and screw caps respectively fitted to the outer ends of said nipples; each detachably engaging the adjacent wedge projection; whereby each wedge may be removed by turning its cap.
5. In an electrical fuse structure; the combination with a casing having hollow metallic screws at its opposite ends; of terminal members in said screws having their inner faces extending in planes which are oblique to the axis of said casing, affording respective wedge abutments; wedges respectively movable in said casing in opposition to said wedge abutments whereby said wedges are adapted to clamp a fuse strip between them and their respective abutments; each of said wedges having means to effect its withdrawal, including a projection from the outer end thereof; screw caps respectively fitted to the outer ends of said screws; each detachably engaging the adjacent wedge projection; whereby each wedge may be removed by turning its cap.
6. In an electrical fuse structure; the combination with a casing having hollow metallic screws at its opposite ends; of terminal members in said screws having their inner faces extending in planes which are oblique to the axis of said casing, affording respective wedge abutments; wedges respectively movable in said casing in opposition to said wedge abutments; whereby said wedges are adapted to clamp a fuse strip between them and their respective abutments; each of said wedges having means to effect its withdrawal, including a projection from the outer end thereof; screw caps respectively fitted to the outer ends of said screws; each engaging the adjacent wedge projection; whereby each wedge may be removed by turning its cap.
7. In an electrical fuse structure; the combination with a cylindrical tubular casing of insulating material; of externally threaded

hollow metallic screws at opposite ends of said casing, each having a cylindrical flange overlapping the end of said casing; means fastening said screws on said casing, including elements extending radially in said flanges and said casing; terminal members in said screws having their inner faces extending in planes which are oblique to the axis of said casing, affording respective wedge abutments; wedges respectively movable in said casing in opposition to said wedge abutments; whereby said wedges are adapted to clamp a fuse strip between them and their respective abutments; each of said wedges having means to effect its withdrawal, including an element projecting from the outer end thereof; screw caps respectively fitted to the outer ends of said screws; each detachably engaging the adjacent element aforesaid projecting from the respective wedge; whereby each wedge may be removed by turning its cap.

8. In an electrical fuse structure; the combination with a cylindrical tubular casing of insulating material; of externally threaded hollow metallic screws at opposite ends of said casing, each having a cylindrical flange overlapping the end of said casing; means fastening said screws on said casing, including elements extending radially in said flanges and said casing; terminal members in said screws having their inner faces extending in planes which are oblique to the axis of said casing, affording respective wedge abutments; wedges respectively movable in said casing in opposition to said wedge abutments; whereby said wedges are adapted to clamp a fuse strip between them and their respective abutments; each of said wedges having means to effect its withdrawal, including an element projecting from the outer end thereof; screw caps respectively fitted to the outer ends of said screws; each engaging the adjacent element aforesaid projecting from the respective wedge; whereby each wedge may be removed by turning its cap.

9. In an electrical fuse structure; the combination with a cylindrical tubular casing of insulating material; of externally threaded hollow metallic screws at opposite ends of said casing, each having a cylindrical flange overlapping the end of said casing; means fastening said screws on said casing, including elements extending radially in said flanges and said casing; terminal members in said screws having their inner faces plane and extending in planes which are oblique to the axis of said casing, affording respective plane wedge abutments; plane faced wedges respectively movable in said

casing in opposition to said wedge abutments; whereby said wedges are adapted to clamp a fuse strip between them and their respective abutments; and internally threaded screw caps respectively screwed upon the outer ends of said hollow screws, and each engaging the adjacent wedge.

10. In an electrical fuse structure; the combination with a cylindrical tubular casing of insulating material; of externally threaded hollow metallic screws at opposite ends of said casing, each having a cylindrical flange overlapping the end of said casing, and having a smooth cylindriform inner face; means fastening said screws on said casing, including elements extending radially in said flanges and said casing; terminal members in said screws having their inner faces extending in planes which are oblique to the axis of said casing, affording respective wedge abutments; and wedges respectively movable in said casing in opposition to said wedge abutments; whereby said wedges are adapted to clamp a fuse strip between them and their respective abutments.

11. In an electrical fuse structure; the combination with a casing having hollow externally threaded screws at its opposite ends; of terminal members in said screws having their inner faces extending in planes which are oblique to the axis of said casing, affording respective wedge abutments; wedges respectively movable in said casing in opposition to said wedge abutments; whereby said wedges are adapted to clamp a fuse strip between them and their respective abutments; screw caps respectively fitted to the outer ends of said screws, rotatable independently of said wedges; and means connecting said wedges with said caps, whereby said wedges may be withdrawn by turning said caps.

12. In an electrical fuse structure; the combination with a relatively stationary wedge element; of a movable wedge element; a rotary screw cap, distinct from said wedge element; and means operatively connecting said wedge with said cap, arranged to permit rotation of said cap with respect to said wedge by compelling said wedge to travel axially with said cap.

13. An end closure for a fuse of the class described, comprising an end cap, and a strip engaging and wedging member carried by the end cap.

In testimony whereof, I have hereunto signed my name at Philadelphia, Pennsylvania, this tenth day of January, 1920.

HOWARD DAVIES.
